UNITED STATES PATENT OFFICE.

CHARLES H. LILLY, OF NEW YORK, N. Y.

LIGHTNING-ROD INSULATOR.

SPECIFICATION forming part of Letters Patent No. 230,290, dated July 20, 1880.

Application filed April 30, 1880. (No model.)

To all whom it may concern:

Be it known that I, CHARLES H. LILLY, of the city of New York, in the county and State of New York, have invented certain new and useful Improvements in Lightning-Rod Insulators, of which the following is a specification.

My invention relates to insulators for insulating rods from the walls or sides of buildings; and the object of my invention is to provide such an insulator, affording greater convenience for application to the rods, and especially for application to rods already put up, to which the ring-insulators in common use are not conveniently applicable, as they have to be slipped over the ends of the rods.

To this end my invention consists in the combination of a glass insulator having an opening through it for a rod, a flat open back adapted to fit against a support and admitting of its being applied transversely to the rod, and a metal strap or staple open at the back, so as to slip over said insulator, and extending entirely around the front thereof for clamping it to a wall or support. In connection with such an insulator I preferably employ a filling-piece, which may be inserted from the top to fill the open back of the insulator, and the filling-piece may have a projecting head to prevent its dropping out of the insulator, and the opening and filling-piece may be dovetailed to prevent the latter from being removed laterally from the back.

In the accompanying drawings, Figure 1 represents a front view of an insulator embodying my invention. Fig. 2 represents a back view thereof. Fig. 3 represents a plan thereof, and Fig. 4 represents a transverse section thereof.

Similar letters of reference designate corresponding parts in all the figures.

A designates the glass insulator having a central opening, *a*, for the rod, and an open flat back, so as to afford convenience for placing it upon a rod laterally or transversely without the necessity of uncoupling the end of the rod and slipping the insulator over the end thereof.

B designates a strap for embracing the in-

sulator A and securing it to a wall or the side 50 of a building. As here represented, its ends are bent outwardly and furnished with holes *b* for the reception of screws or nails; but in lieu thereof a staple having pointed ends to be driven into a wall might be used. The 55 strap or staple, which is open at the back so as to afford provision for slipping it over the insulator, extends entirely around the front thereof, and affords a cheap and easily-applied means for securing the insulator to a 60 support.

To hold the piece A more securely it is constructed with a recess, *c*, in which the strap B fits.

The open back of the insulator may be left 65 open, but is preferably closed by means of a filling-piece, *C*, adapted to be inserted from the top after the insulator is applied to the rod.

In order to prevent the filling-piece from dropping through when it fits loosely, I construct it with a head or flange, *d*, and provide the piece A with a rabbet or recess, *e*, into which said head or flange fits, and if desirable the opening in the back and the filling-piece may be wedge-shaped or taper, as shown 75 clearly in Fig. 2.

The opening in the back and the filling-piece are preferably correspondingly dovetailed, as shown in Figs. 3 and 4, so that the filling-piece may not be removed laterally from 80 the back.

By my invention I furnish an insulator which may be easily applied to a rod without the necessity of uncoupling the rod and slipping the insulator over the end, and which, in consequence thereof, may be cheaply applied.

What I claim as my invention, and desire to secure by Letters Patent, is—

1. The combination of a glass insulator having an opening through it for a rod, a flat 90 open back adapted to fit against a support and admitting of its being applied transversely to the rod, and a metal strap or staple open at the back so as to slip over said insulator, and extending entirely around the 95 front thereof, for clamping it to a wall or support, substantially as specified.

2. The combination of a glass insulator

having an opening through it for a rod, and
an open back, a strap or staple for clamping
the insulator to a building, and a filling-piece
fitting said open back and having a flanged
5 head, substantially as specified.

3. The combination of the glass insulator
A, constructed with a central opening, a, and
a dovetailed and taper opening in the back, of

the strap or staple B, and the wedge-shaped
dovetailed filling-piece C, constructed with a 10
flanged head, substantially as specified.

C. H. LILLY.
